UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,378,075.

Specification of Letters Patent. Patented May 17, 1921.

Application filed February 16, 1920. Serial No. 358,884.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to buttons, and particularly to buttons of that class, which are 10 adapted to be permanently secured to cloth or other material by means of a fastener in the form of a tack, and which are secured in place by means of an automatic button attaching machine. In buttons of this type it has heretofore been a practice to construct 15 the button entirely of metal. I have found, however, that although the body of the button be plated or otherwise protected, this 20 coating will in time wear off and under certain adverse conditions will discolor and damage the material to which the button is attached.

It is accordingly an object of my invention 25 to provide a button, which is so constructed that the parts thereof will not discolor nor damage the material to which the button is secured and therefore the button will present a pleasing and uniform appearance, although the surface thereof has been 30 considerably worn.

A further object is to provide a button, which may be more economically produced 35 than similar buttons as heretofore constructed, will be lighter in weight, of uniform color throughout, and substantially chemically inert.

A further object is to provide a button of 40 the class described, which is partially composed of non-metallic parts, and partially composed of metal parts, the arrangement being such that the button will be light in weight, and may be securely fastened and attached to cloth and other material, by a 45 metallic fastener and will, when secured in place present a neat and pleasing appearance, will be rugged and durable in use, and capable of withstanding shocks and abrasions, such as it will necessarily receive in 50 service.

With the foregoing and other objects in view, which will appear as the description proceeds, my invention resides in the novel button illustrated and described in the ac-

companying drawings and specifications, 55 and in the combination and arrangement of parts thereof, and in the details of construction, all as hereinafter described and claimed, wherein it is to be understood that changes may be made in the scope of what is claimed, 60 without departing from the spirit of the invention.

The preferred embodiment of my invention 65 is illustrated in the accompanying drawings, wherein:

Figure 1 is a view in vertical longitudinal section of a button embodying the characteristic features of my invention.

Fig. 2 is a similar view, showing the fastener firmly anchored in place.

Fig. 3 is a top plan view of the foregoing, parts being broken away to more fully illustrate the construction, and;

Fig. 4 is a detail view in perspective of the 70 non-metallic anchor of the button.

Fig. 5 is a view in vertical section of a somewhat modified form of button.

Fig. 6 is a similar view of a further modification thereof.

Referring specifically to the several views, 80 wherein similar reference numerals designate corresponding parts throughout, my improved button is composed of the body 10, which is formed with the top 11, hub 12, and base 13; a hole 14, extending axially through 85 the latter.

The body of the button as thus constructed is formed of a non-metallic material, which is hard, substantially chemically inert, so as to resist the corroding effect of moisture and 90 to this end is preferably formed of fiber, such as may be pressed, molded or otherwise formed to shape and in an economical manner, and due to the relatively low cost of such material, and the ease with which it may be worked, it has been found that the body of the button as thus composed, may be produced more economically than a similar button composed of metal, and in addition incorporates the advantages as herein described.

Located within the hub 12, is the anchor 15, also formed of a material similar to the body, and has extending therethrough an opening 16, which is bell-mouthed or conical at its end as at 17. Extending upwardly from the top 11 of the body of the button is the flange 18, which receives the metallic

die or anvil 19, the latter being held firmly in place by a metallic cap 20, the rim 21, of which extends over and engages the upstanding flange 18 of the body. The metallic cap 20 may be suitably inscribed and serves to hold the anvil and anchor firmly in place.

With the button as thus constructed and when placed in an automatic button attaching machine, the fastener 22, which includes the fastener prong 23, will be driven through the cloth or material A to which the button is to be attached, and as illustrated in Fig. 2, the upper extremity of the fastener prong upon contacting with the metallic anvil 19, will be turned and headed upon itself as at 24, and which head extends into contact with and firmly engages the anchor 15 and by means of which the fastener is firmly held in place and the button secured and attached to the material A.

The body of the button being formed of material of fibrous nature is of uniform color throughout, and so will present a pleasing appearance even if the surface thereof be slightly scratched, marred, or worn. Further the anchor and body being formed of non-metallic material renders the entire button light in weight and more economical to produce than buttons as heretofore constructed.

In some instances I have found it desirable to form the body 12 and anchor 15 in one piece, such as illustrated in Fig. 6, wherein the body 40, which is formed of non-metallic material is provided with the hole 41, extending therethrough, which enlarges at its upper end as at 42. A metallic anvil is placed directly above the enlarged opening 42 of the body and is held in place by the cap 44, which latter may be suitably inscribed or in other ways finished so as to present a pleasing appearance.

A further modification is illustrated in Fig. 5 wherein the body 31 is formed of metal and contains therein the anchor 32 formed of non-metallic material. The anchor is provided with the opening 33 ex-

tending therethrough, which alines with the opening 34 in the base, so as to receive therethrough the prong of a fastener and guide it against the metallic anvil 35, the latter being held in place by the cap 36.

Having thus described my invention, what I claim is:—

1. A button of the character described, comprising a body portion including a top, a hub, and a perforated base, formed of non-metallic material, an anchor located within said hub, formed of non-metallic material, having an opening extending therethrough, which opening is bell-mouthed at its upper end, a metallic anvil mounted upon the top of said body portion and a metallic cap engaging the said body portion and anvil, and holding the latter and said anvil in place.

2. A button of the character described comprising a body portion including a top, a hub, and a perforated base formed of non-metallic material of uniform color throughout, a metallic anvil located upon the top of said body portion, a non-metallic anchor within said hub, contacting with said anvil, a metallic cap engaging said body portion and holding said anvil in place, said anchor provided with an opening enlarged at its end and extending therethrough, and adapted to receive the prong of a metallic fastener therethrough, which latter is adapted to be headed by said metallic anvil.

3. A button of the class described comprising a body portion formed of non-metallic material, having an opening extending therethrough and enlarging at its upper extremity, a metallic anvil located upon the top of said body, and a top engaging said body and holding said anvil in place.

Signed at Waterbury, in the county of New Haven, and State of Connecticut, this 2nd day of Feb., A. D. 1920.

FRANKLIN R. WHITE.

Witnesses:

LEWIS J. HART,
F. G. PURINTON.
